[57] **CLAIM**

The ornamental design for a foldable tray unit for a product merchandising display stand, as shown and described.

DESCRIPTION

FIG. 1 is a perspective view of a foldable tray unit for a product merchandising display stand showing my new design in its folded position for use;

FIG. 2 is a side elevational view thereof, the sides not shown being identical in appearance thereto;

FIG. 3 is a top plan view thereof;

FIG. 4 is a bottom plan view thereof;

FIG. 5 is a top plan view thereof in an unfolded condition; and

FIG. 6 is a perspective view thereof in its folded position for use wherein a display stand has been shown in broken lines for illustrative purposes only.
